United States Patent Office

Des. 187,850
Patented May 3, 1960

187,850

PILE FABRIC FLOOR COVERING

Harold E. Wadeley, Irvington-on-Hudson, N.Y., assignor to The Firth Carpet Co., Inc., New York, N.Y., a corporation of New York

Application December 4, 1958, Serial No. 53,646

Term of patent 14 years

(Cl. D92—4)

The single figure is a plan view of a pile fabric floor covering showing my new design.

I claim:

The ornamental design for a pile fabric floor covering, substantially as shown.
